A. G. THOMAS

VACUUM TUBE AND TUBE CIRCUITS

Filed July 25, 1923

Inventor:
Albert G. Thomas,
by Geo. H. Evans,
Atty.

UNITED STATES PATENT OFFICE.

ALBERT G. THOMAS, OF LYNCHBURG, VIRGINIA.

VACUUM TUBE AND TUBE CIRCUITS.

Application filed July 25, 1923. Serial No. 653,724.

This invention relates to new and improved thermionic tubes and tube circuits for use in radio telephony and telegraphy, wire telephony, and other purposes; and to methods of using the same.

One of the objects of this invention is to produce a tube which uses the electronic stream as a trigger for the release of a current flow through a resistance which is ionized or otherwise varied by electronic bombardment. Another object is to provide a tube and tube circuit in which the capacity effects in the filament-plate circuit are ameliorated.

With these and other objects in view, I have conceived the structures and circuits as illustrated in the exemplifications of the accompanying drawings, in which:

Fig. 1 is a diagrammatic view showing the tube with its related circuit;

Fig. 2 is a view showing a modified circuit, with a slight modification in the tube;

Fig. 3 shows a simplified form of the tube, with a related circuit;

Fig. 4 is a diagram of a method of connecting the tube and the receiver by means of a bridge.

In the drawing, 1 designates an evacuated vessel containing the several elements. F is the filament, G the grid, E the auxiliary plate, and P the plate. The filament F is fed by a suitable battery A with a rheostat R for regulating the current delivered to the filament. An antenna circuit is shown with the antenna 8, a series condenser C', inductance L', and the ground 11. The inductance L' is shown as electromagnetically coupled to the variably positioned secondary inductance L², which may be tuned by the variable condenser C². This constitutes a usual receiving circuit for feeding the grid G through the grid condenser 15 with a grid leak 14 to allow some of the electrons to escape from the grid G and thus regulate its "free" potential, and a battery C; a short-circuiting switch 17 is provided to eliminate the effect of the grid leak and grid condenser when desired. The other terminal of the inductance L² is connected with the filament F in the usual manner, with the interposition of an inductance coil L³.

The auxiliary plate E comprises a thin-walled tube 2 of aluminum, or other suitable material which permits the passage of elec-

trons but not the passage of gas molecules. It is disposed within the evacuated vessel 1, between the grid G and the plate P. It may be spherical or cylindrical to conform to the shape of these elements, and is supported in any appropriate manner. The particular form and support for this auxiliary plate may be varied within wide limits, and I have shown it diagrammatically as being interposed in its proper location within the evacuated tube. It has electrodes M and N at the ends, and is filled with material 23 which varies in resistance according to the impact of the electronic stream upon it. A suitable material for this purpose is a solid such as finely granular sodium, closely packed and with each grain partially or wholly insulated by a thin insulating film or coating of suitable material such as thin enamel; or liquids such as solutions of nickel sulfate or sodium chloride; or gases such as mercury vapor. When solids are used, as shown in Fig. 2 I prefer to omit the enclosing tube 2, and to build up a coherent body of these granules as a very thin self-supporting sheet or a thin layer of the fine particles mounted on a sheet of insulating material, so as to provide practically a surface conductor; to enable the field from a separate plate P to pass, these bodies may have slots or perforations.

Ordinarily, with a proper potential between the terminals M and N, very little or no current will flow through the element E. When electrons from filament F strike the gaseous molecules, for example, contained in the tube, some of them will be ionized and result in additional carriers of electricity. The effective electrical resistance between electrodes M and N will thus be materially decreased, and a greater current will flow. A similar action occurs with solids or liquids; a movement of the electrons alone occurring in the case of the solids.

The terminals M and N of the auxiliary plate E are brought out through the walls of the evacuated vessel in known manner, and are connected so as to place the element E in series with an inductance L⁴ which is in electromagnetic relation to the inductance L³, with the telephone or other receiver T, and a telephone battery B', and possibly with a suitable regulating resistance R'.

The plate P is connected to a filament lead

with the interposition of a suitable battery B or other source to create an electrostatic field between the filament and the plate.

The operation of this tube and the circuit of Fig. 1 may be stated as follows: When a wave strikes the antenna 8, currents flow as with the ordinary tube, and the electronic stream between the filament F and the plate P, as generated and controlled by the heating of the filament F, the electrostatic action of the battery B and the charge on grid G, is caused to fluctuate in correspondence with the variation in intensity of this wave. The plate P is at a positive potential with regard to the filament and acts solely to create the electrostatic field, which draws the electrons towards the auxiliary plate E. The impact of the electronic stream upon the material of the auxiliary plate causes a variation of resistance in this material in proportion to the electron bombardment, by ionization or otherwise, and thereby effects a change in the intensity of the current flow from the battery B' through the receiver T. This causes the telephone to reproduce the wave as a sound.

I have shown the element E as connected in series with an inductance L⁴, which feeds back or regenerates into the secondary circuit by its coupling with the inductance L³.

In Fig. 2 is shown a simplified circuit. The current from a secondary circuit such as that of Fig. 1 is delivered to the input terminals 30, 31, and causes a change of resistance in the auxiliary plate E as before. The plate P has been disconnected, and the auxiliary plate E is connected in series with telephone T and the battery B'. The wave is detected by the variation in resistance of the auxiliary plate.

Fig. 3 shows a circuit wherein the tube is used with only three elements. The battery B is used to create an electrostatic field between the filament and the auxiliary plate E, which in this case also serves as a plate, and is positive with regard to the filament. The electrons then strike E with great velocity if the potential of B is sufficiently high. This arrangement has the advantage that the electrostatic field is not obstructed. The connection of E with the regenerative coil L⁴ and the battery B' are otherwise as in Fig. 1. The switch S' and the resistance R² are for the purpose of grounding E when desired.

Fig. 4 shows a further modification of the circuits which may be utilized with this tube. In it, the telephone T is connected across a current bridge composed of resistances R³ and R⁴. A third resistance R⁵ connects the telephone T with one terminal M of the element E, while the other terminal of the telephone T and terminal N of the element E are connected directly. At the midpoint of the bridge R³, R⁴ is connected the battery

B', whose other terminal is connected to the resistance R⁵ at the far side from the telephone T. This bridge operates similarly to that used with selenium cells for photo-electric purposes.

In Fig. 1, I have also shown a screen S interposed between the filament F and the grid G; and in Fig. 2 between the grid and the element E. This screen S may be fashioned of material suited to the material of which the filling for element E is made, but may be omitted in certain cases, such as for example when the material of E is a gas not sensitive to light. When using an element E of, for example, sodium, a substance which gives off electrons under the influence of light, the response to the electronic stream is made more complete if the screen is made of a material opaque to light but transparent to the electrons, such as very thin asbestos or cloth treated so as to be uninflammable and dyed dark. This screen S might, however, be composed of a substance such as the zinc sulfide used in the spintharoscope, in which case the impact of the electrons causes the screen to glow, and thus acts upon the photo-electrically responsive device E disposed behind it, by causing a change of resistance.

It should be understood in connection with the above that at least two results may occur when an electron moving at high velocity encounters an obstacle such as the plate elements described above: (1) heat is produced which may vary the resistance by the thermal change of conductivity, (2) a number of electrons may be liberated to move at a low velocity, and by their movement vary the effective resistance of the plate element. The first may be accounted for theoretically as the impact of the electron upon a molecule, and the bringing of the latter into agitation. The second is an inter-electronic collision, and may occur with a serious disturbance of a molecule, or the production of heat: it also far predominates in effectiveness over the former, and is in general the effect upon which depends the operation of the plate element.

What I claim is:

1. In a thermionic tube, an electron-emitting cathode, means to vary the emitted stream of electrons from said cathode at radio frequencies, a plate element in the path of the varying stream of electrons, said plate element being of material adapted to liberate free electrons in its mass in proportion to the varying impact of said stream so that its conductivity varies in proportion to the variation of the emitted stream of electrons, and means to include said plate element in a circuit.

2. In a thermionic tube, an electron-emitting cathode, a grid, a plate, said grid having potentials fluctuating at radio frequen-

cies impressed thereon, means to create an electrostatic field between said cathode and said plate, an element in the path of the electrons passing from said cathode to said plate, 5 said element being composed of material adapted to liberate free electrons in its mass in proportion to the fluctuating impact of said stream so that its conductivity varies in proportion to the variation of the emitted 10 stream of electrons, and means to include said plate element in a circuit.

3. In a vacuum tube system including an electron discharge tube having a cathode, grid and plate elements, said grid having potentials fluctuating at radio frequencies impressed thereon, means to create an electrostatic field between said cathode and said plate elements, an output circuit including said plate element in series therein, said 15 plate being composed of material adapted to have free electrons liberated in its mass in proportion to the fluctuating impact of the electronic stream from said cathode thereupon so that its conductivity varies in 20 proportion to the variation of the emitted stream of electrons, whereby the series resistance of said output circuit is varied in the same proportion.

4. In an electron discharge tube system, an 25 electron-emitting cathode, a grid, a plate, an input circuit connected across the cathode and the grid to impress potentials fluctuating at radio frequency upon said grid with respect to said cathode, a space circuit 30 having a source of electricity therein and connecting said cathode and said plate to create an electrostatic field therebetween, an

element disposed in the path of the electronic stream passing from said cathode to said plate under the action of said field and located between the said grid and the said plate, said element being composed of material electrically responsive to the fluctuating impact of the electronic stream and in proportion thereto, and an output circuit 40 including said element in series therein.

5. In an electron discharge tube system, an electron-emitting cathode, means to vary the stream of electrons emitted from said cathode at radio frequencies, an element disposed in the path of said emitted stream, said element being composed of ionizable material, and a circuit including in series said element and a device to indicate the rate of ionization in said element caused by the 45 fluctuating impact of said stream thereupon.

6. In an electron discharge tube, means for emitting a varying stream of electrons, and an element composed of a material having the high ionization characteristics of sodium in the path of said stream and electrically connected in series in the output circuit of said tube, the resistance of said material changing in substantial accordance with the rate of impact of the varying stream 50 thereupon.

7. In a thermionic tube, an electron emitting cathode, and an element whose resistance is changed by the impact of the electronic stream, and a light-opaque screen disposed between said cathode and said element.

In testimony whereof I affix my signature.

ALBERT G. THOMAS.
